UNITED STATES PATENT OFFICE

HUGO HERZ, OF CHICAGO, ILLINOIS.

DESIGN FOR A GAS-LAMP BODY.

SPECIFICATION forming part of Design No. 36,111, dated October 14, 1902.

Application filed September 17, 1902. Serial No. 123,785. Term of patent 7 years.

To all whom it may concern:

Be it known that I, HUGO HERZ, a citizen of the United States, residing at Chicago, in the county of Cook and State of Illinois, have 5 invented and produced a new, original, and ornamental Design for a Gas-Lamp Body, of which the following is a specification, reference being had to the accompanying drawing, forming a part thereof.

10 The drawing represents in side elevation my new, original, and ornamental design for a gas-lamp body.

As shown in the drawing, the leading or material feature of my design consists in a 15 vertical nipple or short column A, having a plurality of branches A', bearing the group of vertical columns A², and ornamental open-work B of enlarged circumference surmounting said columns.

20 Minor features of my design are the vertically-scalloped depending portions a of the columns A², the knurled portions a' thereof, the swelled portions a² thereof, having perforations a³ and scallops a⁴, the depending

25 knurled knobs a⁵ at the bases of the columns A², the circular base b of the open-work B, the O-shaped figures b', supported on vertical members b², the vertical members b³, having triangular rounded upper ends supplied

30 with triangular perforations b⁴, the basin-shaped perforations b⁵, located vertically above the spaces between the members b³, the perforations b⁶ between the lower portions of the perforations b⁵, the projecting annular bead b⁷, the fanciful I-shaped perforations b⁸ above said bead, the interposed moon-shaped perforations b⁹, having points at the centers of their concavities, and scalloped top edge b¹⁰, presenting outturned points b¹¹. 35

An additional minor feature is the cylindrical member c and columns c' surmounting the same, all within the open-work B and presenting a background visible through the open-work. 40

45 Having described my invention, what I regard as new, and desire to secure by Letters Patent, is—

The ornamental design for a gas-lamp body, as herein shown and described. 50

In testimony whereof I have signed my name to this specification in the presence of two subscribing witnesses.

HUGO HERZ.
